DESIGN FOR A DRY-CELL CABINET

Application filed April 19, 1929. Serial No. 30,949. Term of patent 7 years.

To all whom it may concern:

Be it known, that we, ABRAHAM I. BARASCH and GEORGE J. SKIMIN, both citizens of the United States of America, residing in borough of Brooklyn, and borough of Bronx, respectively, city and State of New York, have invented a new, original, and ornamental Design for Dry-Cell Cabinet, of which the following is a specification, reference being had to the accompanying drawing, forming part thereof.

Figure 1 is a perspective view of a cabinet showing our new design.

Figs. 2 and 3 are respectively, views in elevation of the panels (corresponding to the one shown in Fig. 1) on the 3rd and 5th sides of the cabinet.

We claim:

The ornamental design for a dry cell cabinet, as shown.

In witness whereof, we have hereunto signed our names.

ABRAHAM I. BARASCH.
GEORGE J. SKIMIN.
